(57) CLAIM

The ornamental design for a table, as shown and described.

DESCRIPTION

FIG. 1 is a bottom perspective view of a table showing the new design;

FIG. 2 is a rear view;

FIG. 3 is a front view;

FIG. 4 is a bottom view;

FIG. 5 is a top view;

FIG. 6 is a right view; and,

FIG. 7 is a left view.

The broken lines in the drawings show portions of the table that form no part of the claimed design.

1 Claim, 7 Drawing Sheets

FIG. 1

FIG. 2

FIG. 3

FIG. 4

FIG. 5

FIG. 6

FIG. 7
